WILLIAM J. SMITH, OF NEW HAVEN, CONNECTICUT, ASSIGNOR TO WM. J. SMITH COMPANY, OF NEW HAVEN, CONNECTICUT, A CORPORATION OF DELAWARE.

ADJUSTABLE REAMER.

SPECIFICATION forming part of Letters Patent No. 783,904, dated February 28, 1905.

Application filed June 3, 1904. Serial No. 211,036.

To all whom it may concern:

Be it known that I, WILLIAM J. SMITH, a citizen of the United States of America, and a resident of New Haven, in the county of New Haven, State of Connecticut, have invented an Improved Adjustable Reamer, of which the following is a specification.

The object of my invention is to construct a simple and efficient adjustable reamer which can be constructed and sold at a moderate expense; and this object I attain in a manner which I will now describe.

In the accompanying drawings, Figure 1 is a longitudinal section of one form of my improved reaming-tool. Fig. 2 is a view of the forward end of the tool, and Fig. 3 is a view of the rear end of the tool. Figs. 4 and 5 are views illustrating two parts of the tool detached. Fig. 6 is a longitudinal section of a modified form of tool, and Fig. 7 is a view of the forward end of the same.

Referring to Figs. 1 to 5, inclusive, A is the stock bored out to the form of a hollow tube, with a central diaphragm or annular shoulder a' . I cut through the body of the stock radial slots B—six, in the present instance—for the reception of the cutter-blades C. In tools of this character—that is, with radial cutters in slots—the latter are cut in the outer end of the stock and closed by a separate front plate held to the stock by screws; but, as will be seen most fully in Fig. 5, I cut the slots wholly within the body of the stock, so that the outer end a' , which confines the cutters longitudinally, is itself a part of the stock. Within the central chamber formed in the forward end of the stock I provide a rotarily-adjustable cam-piece D, which, as will be seen by reference to Figs. 2 and 4, has around its circumference a series of cam-faces corresponding in number with the number of the cutters. The inner edges of the cutters C are arranged to bear against these cam-faces, so that by turning the cam-piece (to the right in Fig. 2) the cutters can be adjusted or forced outwardly to ream out holes of increased diameter or to make up for the wear and grinding of the cutters. In conjunction with these expanding-cams I provide means for firmly

clamping the cutters to the cams in any position to which they have been adjusted. For this purpose I prefer to form on the cam-piece D itself, midway of its length, an annular undercut portion E with an inclined face e , Fig. 1, with which can engage the corresponding inclined face of a tongue c , projecting from the back edge of each cutter, Fig. 1.

In the modification shown in Fig. 6 I have shown the tongue with inclined face e' formed by cutting a notch into the back of each cutter, and in that case the annular undercut portion with inclined face E' has to be formed of a diameter greater than the cammed portion of the cam-piece D'.

In either construction it will require but slight longitudinal movement of the cam-piece D D' to draw the cutters inwardly and clamp them firmly to the cam-faces through the action of the inclines just described. Various devices may be employed for producing this longitudinal movement. Thus in Figs. 1 to 5 I have shown the cam-piece D as provided at its inner end with a threaded bolt projecting through the central diaphragm or annular shoulder and having threaded onto it a nut F, which bears against the rear side of that diaphragm or shoulder, so that by turning this nut the cam-piece D may be drawn longitudinally inward to cause the cutters to be clamped firmly to the cam-faces and also to lock the cam-piece in the position to which it has been rotarily adjusted.

In the modification illustrated in Figs. 6 and 7 I have shown the cam-piece D' as made tubular and having passing through it a headed bolt F', the inner end of which is threaded into the diaphragm a' , so that by turning this bolt the cam-piece D' may be drawn longitudinally inward into the stock to clamp the cutters firmly onto their respective cam-faces on the piece D' and the latter also locked in the position to which it has already been adjusted rotarily.

The cam-piece D D' in either construction may be provided on its outer end with suitable holes t , to which a key may be applied to turn the cam-piece rotarily, and the outer face of the cam-piece, together with the adjacent

outer face of the stock, may, as shown in Figs. 2 and 7, be provided with graduations to indicate the rotary adjustment.

Although I have described my invention with particular reference to reamers which have cutters with plane cutting-faces, it will be readily understood that my invention may be applied to other like tools, such as taps.

I claim as my invention—

- 10 1. The herein-described cutting-tool, comprising a stock, having radially-adjustable cutters, a central rotary cam-piece free to be adjusted longitudinally within the stock and having cam-faces against which the cutters bear, and means to clamp the cutters to the said cam-faces by a longitudinal movement of the cam-piece.
- 15 2. The herein-described cutting-tool, comprising a stock having radially-adjustable cutters, a central rotary cam-piece having cam-faces against which the cutters bear, and adapt-

ed to be adjusted longitudinally within the stock, the cutters and cam-piece having inclined engaging faces to clamp the cutters to the cam-faces by longitudinal adjustment of 25 the cam-piece.

3. The herein-described cutting-tool, comprising a stock having radially-adjustable cutters, a rotary cam-piece having cam-faces to adjust the cutters outwardly, inclined engaging faces on the cam-piece and the cutters to clamp the cam-piece and cutters together by the endwise movement of the cam-piece, and means for drawing the cam-piece longitudinally in the stock and locking it. 30

In testimony whereof I have signed my name to this specification in the presence of two subscribing witnesses.

WILLIAM J. SMITH.
